LOCOMOTIVE STRUCTURE

Clement W. Kell, Ridley Park, Pa., assignor to
 General Steel Castings Corporation, Granite
 City, Ill., a corporation of Delaware

Application September 17, 1931, Serial No. 563,293

19 Claims. (Cl. 105—44)

This invention relates to railroad rolling stock and consists particularly of novel cylinder saddle construction for the rear unit of a Mallet articulated compound locomotive.

In the Mallet locomotive, the high pressure cylinders are located in the rear engine cylinder unit and an intercepting valve serves to direct exhaust from the high pressure cylinders through the receiver pipe to the low pressure cylinders in the front engine cylinder unit. Previously cylinder saddles for the rear units of this type of locomotive have been made in two sections bolted together on a vertical longitudinal plane and mounted on the locomotive frame. The steam chambers or housings for the intercepting valve, reducing valve, and emergency valve interconnect and form one large chamber or housing which is located in the left hand saddle section and extends in a horizontal longitudinal direction with the reducing valve located at the rear, the emergency valve at the front, and the intercepting valve between the two.

The exhaust steam passageways extending from the cylinder in the right hand saddle section merge into a single outlet portion having an opening through the rear wall of the section and one end of a separate U-shaped pipe on the outside of the saddle is connected to this outlet portion. The other end of this U-shaped pipe is connected to an inlet portion of a passageway in the left hand cylinder saddle section, which latter passageway extends from the rear wall of the left hand section to the intercepting valve chamber. The exhaust steam passageways from the cylinder to the left hand section merge into a single passageway which in turn merges with the above mentioned passageway leading to the intercepting valve chamber. A longitudinally extending passageway is located in the left hand section and extends substantially the full length of the saddle from the intercepting valve chamber to the front wall where it connects with the receiver pipe, all of which is shown in Locomotive Cyclopedia of 1925, page 541.

The main object of the present invention is to simplify the cylinder saddle structure including the steam passageways and intercepting valve chamber. This object is accomplished substantially by forming the entire cylinder saddle integrally thereby eliminating the joint between the right and left hand portions, by running the single merged portion of the exhaust steam passageways from the right hand cylinders directly to the intercepting valve chamber, thereby eliminating the above mentioned U-shaped pipe at the rear of the saddle and locating the steam passageway inside of the saddle where the steam will better retain its heat and maintain the desired pressure, and by locating the reducing valve in the front portion of the saddle instead of in the

rear and the emergency valve in rear portion instead of front, thereby greatly reducing the length of the passageway extending from the intercepting valve to the receiver pipe.

Another object is to reduce the weight and the amount of fitting and machining which is necessary in previous structures and to increase the strength and rigidity of the structure.

Another object is to simplify the boring of the intercepting, reducing, and emergency valves when the cylinder saddle structure is formed integral with the locomotive underframe or bed. This is accomplished by relocating the reducing valve, having a larger bore than the intercepting and emergency valves, in the front portion of the cylinder saddle whereby the valve chambers may be readily bored from the front avoiding the locomotive bed which extends rearwardly of the saddle.

Another object is to form the jaws or pocket for the Mallet hinge connection integral with cylinder saddle.

These objects and other detail objects are attained in the structure illustrated in the accompanying drawings in which—

Figure 1 is a top view of a cylinder saddle for a Mallet rear unit.

Figure 2 is a front end view of the same.

Figure 3 is a horizontal section taken substantially on the line 3—3 of Figure 4.

Figure 4 is a vertical transverse section taken on the line 4—4 of Figure 3.

Figure 5 is a vertical longitudinal section taken on the line 5—5 of Figure 2.

Figure 6 is a similar section taken on the line 6—6 of Figure 2.

Figure 7 is in part a side view and in part a vertical longitudinal section taken on the line 7—7 of Figure 4.

Figure 8 is a detail horizontal section taken on the line 8—8 of Figure 2.

Figures 9, 10, and 11 are vertical transverse sections taken on corresponding section lines of Figure 1.

Figure 12 is in part a top view and in part a horizontal section taken on the line 12—12 of Figure 13 and illustrating a modified form of the invention.

Figure 13 is a front view of the same.

Figure 14 is a side view of the same.

Figure 15 is in part a top view and in part a horizontal section taken on the line 15—15 of Figure 16 and illustrating another modification.

Figure 16 is a front view of the same.

Figure 17 is a side view of the same.

Figures 18, 19, and 20 correspond to Figures 15, 16, and 17 and illustrate another modification.

Figures 1 to 11, inclusive, illustrate one form of the invention in which high pressure cylinders

1 and 2, steam control chests 3 and 4 therefor, and boiler saddle support 5 are formed integrally with underframe side members 6 of the rear unit. Located within saddle support 5 near the right hand chest 4 is an intercepting valve chamber 7 having a passage 8 at the front end thereof leading to an outer ball joint element 9 for connection with a receiver pipe (not shown). Pads 10 are provided directly rearwardly of the intercepting valve chamber for supporting the emergency exhaust valve which extends through openings 19 in chamber 7. The exhaust valve seats in opening 20a, the intercepting valve seats in opening 20, and an opening 21 in the front wall 15 of the saddle support provides a seat for the reducing valve.

Exhaust passages 11 leading from the ends of left hand steam chest 3 extend inwardly and downwardly through the saddle and merge at 12 20 in a single passage 13 curving upwardly into chamber 7. Exhaust passages 14 leading from the right hand chest 4 extend substantially horizontally inwardly through the saddle and merge in a single passage 15 connecting with chamber 25 7. A projection 16 at the intersection of the bottom walls of passages 13 and 15 serves to direct steam upwardly into chamber 7 and a cut out portion 17 is provided in the projection to permit condensate to drain from passage 15 to passage 30 13 and thence outwardly of the saddle through an opening 18 in the bottom of passage 13.

Also extending inwardly to chamber 7 from right hand steam chest 4 and between exhaust passages 14 is a live steam passage 22 forming a branch of live steam line 23 which receives saturated steam directly from the boiler. An outlet 24 from chamber 7 connects with an exhaust pipe (not shown) leading to the smokestack and a passage 25 paralleling the wall of chamber 7 provides for conducting live steam from passage 22 through the reducing valve to the forward or low pressure cylinders.

It will be understood that in starting the locomotive, all cylinders are supplied with live steam 45 and, after a few revolutions of the drivers, the low pressure cylinders will be automatically changed over to exhaust steam by the intercepting valve.

The female end 26 (see Figure 5) of the Mallet 50 articulated hinge is formed integrally with the front portion of the boiler support and directly beneath a receiver pipe ball joint element 9. The hinge member 26 has spaced horizontal walls for receiving the cooperating hinge member on the 55 rear end of the front unit and has openings 27 for the connecting pin.

This arrangement of the intercepting valve chamber 7 with the larger openings in the front end facilitates boring, particularly where the cylinder saddle is formed integrally with the frame. The location of the reducing valve in the front 60 part of chamber 7 and of the passage 8 within the saddle support permits the elimination of the usual U-pipe at the rear of the cylinders and also 65 eliminates the section of the receiver pipe passing through the saddle. The downward and then upward curving of the exhaust pipes from the left hand cylinder serves to guide the flow of the exhaust steam directly into the intercepting 70 valve and thereby reduces back pressure in the cylinders.

In Figures 12, 13, and 14, the intercepting valve chamber 126 is disposed with its longer axis 75 extending transversely of the boiler saddle and is cast integrally with outer ball joint element

27' and with boiler saddle 28, high pressure cylinders 29 and steam control chests 30. The cylinder saddle is cast integrally with the underframe 36. The combination valve chamber and ball joint structure is spaced forwardly from the front wall of the saddle and directly above hinge element 51. Exhaust passages 31 from the steam chests 30 curve upwardly and inwardly through the boiler saddle and merge in a single passage 48 leading into the intercepting valve chamber. An exhaust steam connection 32 is provided on the right end of chamber 126 and live steam is conducted through a pipe 33 connecting with auxiliary opening 34 in the left hand chest 30 and the opening 35 in the valve chamber. 10 15

The form shown in Figures 15, 16, and 17 corresponds with that shown in the figures just described except that the cylinder saddle including boiler support 38, cylinders 40, steam chests 39, intercepting valve chamber 41, and ball joint 20 outer element 42 is formed separately from the underframe. The structure is provided with the usual mounting elements for engagement with underframe longitudinals 37.

Figures 18, 19, and 20 are similar to Figures 25 15, 16, and 17 except that exhaust passages 45 leading from the front ends of chests 46 extend inwardly at right angles to the axis of the underframe and merge with the intercepting valve body structure 49. Passages 47 leading from 30 the rear ends of chest 46 extend diagonally through the boiler support 50 and merge with passages 45 in the central front portion of the saddle. The combination intercepting valve chamber and ball joint structure is supported 35 by exhaust passages 45 and by a rearward extension 43 on the ball joint outer element 44.

As in the preferred form illustrated in Figures 1 to 11, the receiver chamber in each of the modifications also houses the reducing and emergency 40 exhaust valves and the receiver pipe extends only to the front end of the high pressure cylinder saddle. The exhaust passages are located substantially in the saddle with the result that the steam is kept hotter than where much of the 45 piping is located outside the saddle. Moreover, the steam passages extend substantially from side to side of the structure and assist in bracing the same. In all of the forms, the structure is rigid throughout and the number of bolted or riveted 50 connections has been reduced to a minimum. It will be understood that the intercepting valve chamber may comprise a chamber for the intercepting valve only or it may include portions for the reducing and emergency valves in addition to 55 the intercepting valve, as illustrated.

Obviously, the invention is not limited to the exact details illustrated in the various forms but may be modified in other ways without departing from the spirit thereof and the exclusive use 60 of all such modifications as come within the scope of the appended claims as contemplated.

What is claimed is:

1. In a locomotive structure, a cylinder saddle, steam control chests on each side thereof, an intercepting valve chamber located between said chests and intermediate the front and rear of said saddle, and exhaust steam passages leading from said chests continuously through said saddle between the front and rear walls thereof to said 65 chamber.

2. Structure as defined in claim 1 comprising an integral metal casting in which the valve chamber and passages brace the saddle and steam 70 chests. 75

3. In a locomotive structure, a cylinder saddle, steam control chests on each side thereof, an intercepting valve chamber located between said chests and closer to one of said chests than the other, an exhaust steam passage leading from the farther chest to said chamber, said passage extending downwardly and transversely inwardly from said chest continuously through said saddle and then upwardly, and another passage extending substantially horizontally from the other chest to said chamber. 5
4. In a locomotive cylinder saddle structure, steam control chests, an intercepting valve chamber between said chests, steam passages leading from said chests continuously through said saddle to said chamber, the lower walls of said passages merging adjacent said chamber, and a projection extending from the merged portion of said walls and serving to direct steam into said chamber. 10
5. In a locomotive cylinder saddle structure, steam control chests, an intercepting valve chamber between said chests, steam passages leading from said chests continuously through said saddle to said chamber, the lower walls of said passages merging adjacent said chamber, and a projection extending from the merged portion of said walls and serving to direct steam into said chamber, said projection having a recess therein for permitting condensate to drain past said projection and out of said chamber. 15
6. In a locomotive structure, a cylinder saddle, steam control chests on each side thereof, an intercepting valve chamber located between said chests and closer to one of said chests than the other, an exhaust steam passage leading from the farther chest to said chamber, said passage extending downwardly and transversely inwardly from said chest continuously through said saddle and then upwardly, and another passage extending substantially horizontally from the other chest to said chamber, each of said passages being bifurcated and the respective bifurcations leading from the opposite ends of said chests. 20
7. In an articulated locomotive integral structure, a cylinder saddle, high pressure steam cylinders, control chests therefor, an intercepting valve chamber within said saddle, a receiver pipe connection in the front portion of said saddle, a steam passage from the front end of said chamber to said connection, and other steam passages for exhaust and live steam leading from said chests continuously through said saddle to said chamber. 25
8. In a locomotive structure, a cylinder saddle, and an intercepting valve chamber within said saddle, the rear parts of said chamber and saddle including elements for mounting an emergency exhaust valve. 30
9. In a locomotive structure, a cylinder saddle, and an intercepting valve chamber within said saddle, the front parts of said chamber and saddle including elements for mounting a reducing valve. 35
10. In combination, a locomotive cylinder saddle having an end wall extending transversely of the saddle, and an integral structure including a steam pipe ball joint element and an intercepting valve chamber, said structure projecting beyond said end wall of said saddle and the longer axis of said chamber substantially paralleling said wall. 40
11. In a locomotive structure, a cylinder saddle, an intercepting valve chamber projecting from the front wall thereof and substantially paralleling said wall, and steam passages extending through said saddle transversely of the locomotive axis to said chamber. 5
12. In a locomotive structure, a cylinder saddle, steam control chests at each side thereof, an intercepting valve chamber adjacent the front wall of said saddle, exhaust steam passages leading from the front end of said chests and paralleling said front wall, and other exhaust steam passages leading from the rear ends of said chests through said saddle and merging with said first mentioned passages, the merged portions of said passages leading into said chamber. 10
13. In a locomotive structure, a cylinder saddle, steam control chests at each side thereof, an intercepting valve chamber adjacent the front wall of said saddle, and exhaust steam passages leading from the front end of said chests and paralleling said front wall and opening into said chamber, all of said parts being integral and said passages at least partially supporting said chamber. 15
14. A locomotive integral structure including a box-shaped underframe longitudinal member, a cylinder saddle, and an intercepting valve chamber, the lower wall of said chamber forming substantially a continuation of the upper wall of said member. 20
15. A locomotive integral structure including a box-shaped underframe longitudinal member, steam control chests at the sides thereof, and an intercepting valve chamber, the upper wall of said member merging with the walls of said chests and said chamber and bracing the same. 25
16. In an articulated locomotive integral structure, a box-shaped cylinder saddle, an intercepting valve chamber therein, a receiver pipe connection on a transverse wall of said saddle, a steam passage between said chamber and said connection and extending along said wall, and other steam passages leading from said chamber towards the sides of said saddle. 30
17. A locomotive cylinder saddle structure including an upwardly disposed transverse wall and an intercepting valve chamber substantially horizontal and paralleling said wall, said saddle wall forming a part of the wall of said chamber. 40
18. In a locomotive structure, a cylinder saddle, a steam control chest on each side thereof, an intercepting valve chamber carried by said saddle and located substantially between the longitudinal axes of said chests, and exhaust steam passages connecting both of said chests with said chamber and located substantially within the body of said saddle. 50
19. In a locomotive saddle structure, steam control chests at the side of the structure, a transverse wall extending between said chests, an intercepting valve chamber carried by said saddle and located intermediate the axes of said chests, and an individual exhaust steam passage leading from each steam control chest directly into said saddle and continuing in said saddle to a point where it merges with the other of said passages in a single cavity leading into said intercepting valve chamber. 60
